US00D960866S

(12) **United States Design Patent** (10) **Patent No.:** **US D960,866 S**
(45) **Date of Patent:** **** Aug. 16, 2022**

(54) **SPEAKER**

(71) Applicant: **Anker Innovations Technology Co., Ltd.**, Changsha (CN)

(72) Inventor: **Li Yao**, Shenzhen (CN)

(73) Assignee: **Anker Innovations Technology Co., Ltd.**, Changsha (CN)

(**) Term: **15 Years**

(21) Appl. No.: **29/747,603**

(22) Filed: **Aug. 24, 2020**

(30) **Foreign Application Priority Data**

Feb. 24, 2020 (CN) 202030057969.9

(51) **LOC (13) Cl.** **14-06**

(52) **U.S. Cl.** **D14/209.1**
USPC **D14/209.1**

(58) **Field of Classification Search**
USPC D14/167, 188, 195, 196, 204, 207, 214,
D14/240, 242; D3/904
CPC H04R 1/02; H04R 3/00; H04R 1/025
See application file for complete search history.

(57) **CLAIM**

The ornamental design for a speaker, as shown and described.

DESCRIPTION

FIG. 1 is a front perspective view of a speaker showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines depicting the remainder of the speaker form no part of the claimed design.
